UNITED STATES PATENT OFFICE

ADOLPH KAUFMAN, OF FAIRFIELD, CONNECTICUT

VALVE-LIFTING TOOL

Application filed February 13, 1930. Serial No. 428,032.

My invention relates to new and useful improvements in valve lifting tools such as are employed for compressing the valve springs in an automobile gasoline engine to insure the easy removal of the valve.

It is an object of the invention to produce a valve spring lifter whose engaging jaws are disposed alike to one side of the alignment of the operating handles so as to be used as a right or left; and thereby be easily applied to a spring from either side, if a direct approach is difficult.

A further feature of the invention is to construct the tool in such a manner as to permit it to be made of strip metal of suitable lengths and shapes; to provide a multiple lever structure including a pair of operating handles and pairs of jaws hingedly and pivotally connected together in a manner to provide increased leverage and ease of operation.

Finally to provide a tool, of the class described, having engaging jaws, the operative end portions of each pair of which are made adjustable with respect to each other, so as to better accommodate springs of different diameters and thereby insure a firmer fitting grasp of the tool with the spring in a way to prevent the same from dropping out; and to further provide for locking the jaws in their various closed positions, in a manner to retain the spring grasped thereby.

With these and other objects in view, the invention resides and consists in the construction and novel combination and arrangement of parts hereinafter more fully described, illustrated in the accompanying drawings, and pointed out in the claims hereto appended, it being understood that various changes in the form, proportion, size, and minor details of construction within the scope of the claims may be resorted to without departure from the spirit, or sacrificing any of the advantages of the invention.

Similar characters of reference denote like or corresponding parts throughout the several figures of the accompanying drawing forming a part of this specification and upon

Fig. 1 shows a side elevation of my improved valve spring lifting tool; and

Fig. 2 shows a top plan view of the same implement.

As before stated, the tool is preferably made of rolled strip steel of suitable proportions, which are cut, swedged and bent to required shapes to provide, when assembled, two operating handle members and two pairs of jaw members, the latter being pivotally connected to the forward ends of the handle members for the purpose of opening and closing the jaws.

Referring in detail to the characters of reference marked upon the drawings, 5 represents the upper handle and 6 the lower handle member, as seen in Fig. 1. These two members are each formed of a single strip of metal which is bent substantially midway of their lengths, to form rounded outer ends 7 and 8 and forwardly disposed parallel side members 9 in spaced relation. The lower handle also includes spaced apart side members 10 and 11 and has secured therein a pivotal stud 12 upon which the enlarged end 13 of a bowed rod 14 is pivoted between said two parallel side portions. The upper handle member is also provided between its forward side portions with a sleeve 15 that has trunnions journaled in holes 16 of the said side members 8 and 9 of the handle and is further provided with a hole 17 through which the before mentioned bowed rod 14 is free to slide as in the opening and closing of the handle.

A slide 18 encircles the upper handle and bowed rod contained therein and is adapted to be positioned on the handle and rod in a way to engage various portions of the rod and hold it against slidble movement in the sleeve and in that manner lock the jaws in various adjusted positions.

The forward ends of the handle portions are bent inward as at 19 to cross each other at substantially a right angle and are each then disposed forward in substantially parallel relation and terminate in pivotal end portions, thus forming each member of a uniform length and at an equal distance from the pivotal stud 20 that passes through the four

members where crossed at a right angle, as before suggested.

In this connection it will be seen that the rear side member 9 of the top handle and the front side member 10 of the lower handle are set inward slightly, as at 21, at the pivotal crossing point of the four members so as to accommodate the straight portions 22 and 23 at this point, of the front member 8 of the upper handle and the rear member 11 of the lower handle, better to insure required clearances and perfect hinged connections.

The head portions of the pivotal stud 20 are positioned between the jaw members in a way to be free of the same during all operations of the same. The clamping jaws as before stated comprise two pairs of jaws, an upper pair formed of two pieces, 24 and 25, and a lower pair formed of a like number of pieces, 26 and 27. The inner end portions of these four jaw members are disposed inward as at 28 and are pivotally connected by a bolt 29 passing therethrough and also through a sleeve 30. The axis of this pivot and that of the pivot 20 at all times remain in longitudinal alignment with the tool. The forward end portions of the four members of the handle are disposed between the jaw members, the two pivotal end portions of the lower handle member being pivotally connected to the upper jaw members 24 and 25 by means of a screw bolt 31, while the forward end portions of the upper handle are likewise disposed between the two lower jaw members 26 and 27, where they are pivotally connected by means of a screw bolt 32.

A spring 33 is mounted on each of the screw bolts 31 and 32 between the end portions of the handle members so as to provide means of adjusting the jaw members of each pair with respect to each other by tightening or loosening the nuts 34 upon the screw bolts and whereby the free engaging end portions of the jaws may be opened or closed, better to accommodate springs of different diameters. Each of the jaws are provided with an inwardly disposed flange 35 in addition to the vertically disposed portion of said jaws, so as to form a seat upon which the opposite sides of the end portions of the spring may be seated.

From the foregoing it will be obvious that in the operation of the tool the jaw members, while in an open position, are inserted in the end portions of the spring, whereupon by the pressing together of the handles the jaws are likewise closed and the spring compressed to the degree required, whereupon the handles are locked in position and the spring removed, thus freeing the valve stem for the removal of the same.

Having thus described my invention, what I claim and desire to secure by Letters Patent is:

1. A valve lifting tool comprising a pair of handle members, each including two forwardly disposed portions which are deflected inward to cross each other and are pivotally connected together and have their end portions disposed forward in substantially parallel relation to each other, two pairs of jaw members having their ends disposed rearward of the pivot connecting the handle members and pivotally connected together, the two members of the upper pair of jaws being pivotally connected substantially midway of their length to the forward end portion of the lower handle members, the two members of the lower jaw being pivotally connected intermediate of their lengths to the end portions of the upper handle, the engaging ends of the jaws of each pair being disposed in spaced relation to each other and in substantially operable alignment with that of the cooperating pair of jaws.

2. A valve lifting tool comprising a pair of handle members, each including two forwardly disposed portions which are deflected inward to cross each other and are pivotally connected together and have their end portions disposed forward in substantially parallel relation to each other, two pairs of jaw members having their ends disposed rearward of the pivot connecting the handle members and pivotally connected together, the two members of the upper pair of jaws being pivotally connected substantially midway of their length to the forward end portion of the lower handle members, the two members of the lower jaw being pivotally connected intermediate of their lengths to the end portions of the upper handle, the engaging ends of the jaws of each pair being disposed in spaced relation to each other and in substantially operable alignment with that of the cooperating pair of jaws, the said jaw members being bent to one side of an imaginary center line extended through the handle and pivotal centers.

3. A valve lifting tool comprising a pair of handle members, each including two forwardly disposed portions which are deflected inward to cross each other and are pivotally connected together and have their end portions disposed forward of said pivotal connection, two pairs of jaw members having their ends disposed rearward of the pivot connecting the handle members and pivotally connected together, the two members of the upper pair of jaws being pivotally connected substantially midway of their length to the forward end portion of the lower handle members, the two members of the lower jaw being pivotally connected intermediate of their lengths to the end portions of the upper handle, the engaging ends of the jaws of each pair being disposed in spaced relation to each other and in substantially operable alignment with that of the cooperating pair of jaws.

atable alignment with that of the cooperating pair of jaws, and means for adjusting the distance between either or both pair of jaw members.

4. A valve lifting tool comprising a pair of handle members pivotally joined together and having forwardly disposed ends, jaw members having their inner end portions pivotally connected together and their intermediate portions pivoted to said forwardly disposed ends, a rod hingedly connected to one of the handle members, a swivel mounted in the other handle and having a hold therethrough to receive and permit of the sliding engagement of the rod, and a slide mounted upon one of the handle members to engage the rod to lock the handles together.

Signed at Bridgeport, in the county of Fairfield and State of Connecticut this 12th day of February A. D. 1930.
